UNITED STATES PATENT OFFICE.

JULIUS F. ADAMS, OF PITTSBURGH, PENNSYLVANIA.

DESIGN FOR ANDIRONS.

Application filed July 19, 1922. Serial No. 3,134. Term of patent 3½ years.

To all whom it may concern:

Be it known that I, JULIUS F. ADAMS, a citizen of the United States, residing at Pittsburgh, in the county of Allegheny and State of Pennsylvania, have invented a new, original, and ornamental Design for Andirons, of which the following is a specification, reference being had to the accompanying drawing, forming part thereof.

The figure is a front view of the andiron showing my new design.

I claim:

The ornamental design for andirons as shown.

JULIUS F. ADAMS.
